KEYHOLE ILLUMINATING DEVICE

George J. Taylor, Cleveland, Ohio

Application June 8, 1932, Serial No. 616,105

2 Claims. (Cl. 240—2.13)

This invention relates to a keyhole illuminating device primarily intended to be applied to the front doors of houses or other buildings.

The invention has for its primary object the provision of an electric illuminating device whereby the keyhole of a door lock may be illuminated at will, and in which the electric current may be easily switched on and off.

A more specific object of the invention is to provide a device of the above kind in which the arrangement and form of parts is simple, and which may be easily applied to a door, the lamp or illuminating device proper being located in a position to minimize danger of breaking or damaging the same.

The invention consists in the novel form, combination, and arrangement of parts hereinafter more fully described, shown in the accompanying drawing and claimed.

20 In the drawing:

Figure 1 is a fragmentary side elevational view of a portion of a door having the present invention applied thereto.

Figure 2 is a view looking toward the right of Figure 1 with the knob and adjacent parts in central longitudinal section; and

Figure 3 is a horizontal section on line 3—3 of Figure 2.

Referring in detail to the drawing, 5 indicates the portion of a door in which the usual locking means is located, the keyhole and escutcheon plate of said locking means being respectively indicated at 6 and 7. The door proper and the locking means may be of any usual or preferred construction, and they form no part of this invention.

In order that a person may be able to locate the keyhole 6 after dark and readily insert the key therein, an illuminating device is provided whereby the keyhole may be illuminated, such illuminating device being electrically operated. As shown, the illuminating device comprises a small electric lamp 8 located adjacent to the keyhole. To minimize the danger of injury to the lamp 8 and also to cause the rays of light to strike the keyhole at an angle so that the latter may be readily located, the lamp 8 is located at the inner side of the outer door knob 9.

To make the device compact, the door knob 9 is hollow and may have a pair of spaced clips 10 therein and attached to the inner wall thereof to receive and support an electric battery 11 in proper position within the knob 9. An insulating covering 12 is placed over the battery, and suitable electrical connections are provided be-

tween the battery and the lamp 8. As shown, a conducting strip 13 extends from the end terminal of battery 11 across the top of the latter and down one side of the same where its free end is directed outwardly at an angle as at 14 to provide a contact arranged to engage the end contact or terminal 15 of lamp 8. The other terminal of the lamp 8 is formed as usual by the threaded part 16 thereof. The threaded shell or part 16 of lamp 8 is threaded into a socket 17 secured to the door knob 9 so as to be in electrical connection therewith, and a push button 18 is mounted in the outer wall of the knob 9 so as to make contact with the other terminal or metallic casing of battery 11 when pushed inwardly, the insulating covering 12 being cut away at this point as indicated at 19. A spring 20 secured on the inside of the outer wall of knob 9 normally holds the push button away from the casing terminal of battery 11, and such spring is in electrical connection with the knob 9 and the inner portion of push button 18 so that the latter is always in electrical connection with the knob. This forms a switch by which the current is normally cut off from the lamp 8, and by which the current may be supplied at will to said lamp. When the switch is closed a circuit is closed through conducting strip 13, lamp terminals 15 and 16, knob 9, spring 20, push button 18 and the casing terminal of battery 11.

As shown clearly in Figure 2, the knob 9 has a reduced attaching stem 21 adapted to receive and to be secured in the ordinary way on the projecting end of the stem or spindle 22 that coacts with the door latching mechanism. As shown, the outer end portion of the stem 21 adjacent the inner side of knob 9 is flared at 22 to provide an inclined wall having an opening 24 in the lower part thereof through which the lamp 8 may be introduced for being threaded in the socket 17 into engagement with the contact 14. The socket 17 extends rearwardly and downwardly from the inner wall of knob 9 so as to align with opening 24 and to position the lamp 8 so that the rays therefrom will strike the keyhole 6 at an angle so that the latter may be most effectively illuminated and thereby readily located. As the lamp 8 barely projects through the opening 24, it is effectively protected from injury by the flared portion 23 of neck 21, the socket 17 being wholly housed within said flared portion 23.

The advantages of the above-described arrangement of parts with regard to compactness and durability of construction, efficiency of illumination, and convenience of operation, will be

readily apparent. The invention may be readily applied to a door already in use, it being unnecessary to change any parts thereof with the exception of the knob, which knob can be readily removed from the spindle 22, and a knob provided with the present illuminating device secured in its place.

To permit the parts to be easily removed, such as is necessary when renewal of the battery is required, the knob 9 may be formed in two parts joined together by a threaded connection as at 25.

What I claim as new is:

1. An illuminating device for the keyhole of a door lock, comprising a hollow metallic door knob having a reduced attaching stem provided with a flared outer end portion, an electric lamp socket carried by and extending inwardly and downwardly from the inner side of the knob and completely housed within said flared outer end portion of the stem, said flared end portion of the stem having an opening in alignment with the lamp socket at the bottom thereof, an electric lamp threaded in said socket, an electric battery disposed in the door knob and having a rear contact engaged by the central terminal of said electric lamp, said socket being in electrical connection with the door knob, a push button at the outer side of and in electrical connection with the door knob, said push button being arranged to be pressed into engagement with the casing terminal of the battery for closing the circuit of

said lamp, an insulating covering on said battery, and spaced clips attached to the inner wall of the door knob and arranged one above the other for receiving and supporting the battery within the knob in an upright position.

2. As a self-contained means for illuminating keyholes at will by a permanently-located push-button operated electric light bulb, said means comprising a unit adapted to be removably secured to the knob spindle of a door, and including a knob formation characterized by a knob and its stem, said knob being hollow and of dimensions to receive the lamp battery and permit the knob to form the sole support for the illuminating means, said knob including a casing having a removable closure carrying the push-button control, said casing forming the grip surface of the knob, the casing carrying a lamp socket the axis of which is inclined to the axis of the knob to cause the lamp rays to directly illuminate the zone of the key-hole, said casing including a wall to which the knob stem is secured by a flared formation, said socket having its inner end secured to said wall and projecting in the direction of the flared portion to locate the socket as projecting exteriorly of said wall, the interior of the socket being accessible for lamp positioning through an opening of the flared portion, whereby the interior of the casing will be free to receive a battery and the essential circuit connections.

GEORGE J. TAYLOR.
